UNITED STATES PATENT OFFICE.

ORRIN B. READ, OF TROY, NEW YORK.

HORSE-TAIL HOLDER.

No. 891,861.

Specification of Letters Patent.

Patented June 30, 1908.

Application filed September 11, 1907. Serial No. 392,374.

To all whom it may concern:

Be it known that I, ORRIN B. READ, a citizen of the United States, residing at Troy, county of Rensselaer, and State of New York, have invented certain new and useful Improvements in Horse-Tail Holders, of which the following is a specification.

The invention relates to such improvements and consists of the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 of the drawings is a plan view of the inner side of my improved horse-tail holder laid out flat. Fig. 2 is a top plan view of the same. Fig. 3 is a front view of the same bent to circular form as in use. Fig. 4 is a horizontal section of the same taken on the broken line 4—4 in Fig. 3.

25 The invention relates more particularly to horse-tail holders made entirely of metal: and the particular object of the invention is to more effectively support the holder upon the tail of the horse.

30 Referring to the drawings wherein the invention is shown in preferred form, 1, represents a strip of resilient sheet-metal of suitable width and length for use as a tail-holder, in the body of which strip are formed a plurality of diamond-shaped apertures, 2, and a plurality of half-diamond-shaped apertures, 3, all of which apertures are arranged longitudinally of the middle portion of the strip, the half-diamond-shaped apertures being located near one end thereof with their diamond-shaped ends pointing toward the center of the strip.

35 The opposite end of the strip is provided with an introverted hook, 4, formed by cutting and inwardly displacing a portion of the body of the strip, said hook being adapted to enter the several half-diamond-shaped apertures and to engage with the square outer end-wall of the aperture within which it is inserted, and thereby to serve as a lock for securing the holder in circular form, as shown in Figs. 3 and 4, to which form the holder is bent in use so as to embrace the tail of the horse.

40 All-metal tail-holders tend to slip and become displaced on the horse's tail, unless

provided with special means to retain them in the proper position.

As a novel means for retaining the tail-holder in position upon the tail of the horse, 60 in use, I provide the holder with a plurality of introverted tongues formed by bending inwardly portions of the body of the strip along certain sides of the apertures 2 and 3.

65 Certain of these tongues, 5, are bent inwardly from such sides of the respective apertures that they incline in one direction while certain other of said tongues, 6, are bent inwardly from such differently located sides of other apertures that they incline in the opposite direction, and the tongues, 5 and 6, are preferably arranged in alternation, 70 as shown, so that they form V-shaped spaces between them and will not pass readily along the hairs of the horse's tail, but will tend to 75 wedge the hairs of the tail between the neighboring tongues, and thereby support the holder in proper position upon the tail.

75 For certain purposes of the invention the shape of the openings is immaterial so long 80 as the tongues are obliquely arranged and inclined some in one direction, and some in another direction.

85 When the holder is applied to the tail of the horse, the strip, 1, is bent to circular form, as shown in Figs. 3 and 4, and clamped around the tail by entering the hook, 4, in the proper aperture, 3; the operation of applying the holder to the tail serving to embed the oppositely inclined tongues, 5 and 6, 90 in the hairs of the tail, the tongues readily entering between the hairs without injury to the same.

95 For certain purposes of the invention it is immaterial whether the inwardly projecting tongues are integral with the body of the holder or not, and for such purposes the holder may be provided in any known manner with inwardly projecting tongues occupying planes inclined obliquely to the plane of the 100 body of the holder.

What I claim as new and desire to secure by Letters Patent is

1. A horse-tail holder comprising a strip of resilient material having means for securing together the ends of the strip when bent to circular form, and having introverted tongues severally occupying planes oblique to the longitudinal axis of the holder.

110 2. A horse-tail holder comprising a strip of resilient material having means for securing together the ends of the strip when bent

to circular form, and having introverted tongues, certain of which are inclined in one direction, and certain others in the opposite direction.

5. 3. A horse-tail holder comprising a strip of resilient material provided with a longitudinal row of apertures, certain of the walls of which are obliquely inclined, and having means for securing together the ends of the strip when bent to circular form, and obliquely inclined introverted tongues formed by portions of the body of the strip bent inwardly along certain of the obliquely inclined walls of said apertures.

15. 4. A horse-tail holder comprising a strip of resilient material provided with a longitudinal row of apertures, certain of the walls of some of which are inclined in one direction, and certain of the walls of others of which are inclined in the opposite direction, and having means for securing together the ends of the strip when bent to circular form, and introverted tongues formed by portions of the body of the strip bent inwardly along the respective oppositely inclined walls of said apertures.

30. 5. A horse-tail holder comprising a strip of resilient material having at one end an introverted hook, and provided near its other end with a row of apertures severally adapted to receive said hook, said apertures being formed each with a square outer end adapted to engage said hook, and with inclined walls at its inner end, said strip having introverted inclined tongues formed by bending inwardly portions of the strip along certain of the inclined walls of said apertures.

35. 6. A horse-tail-holder having inwardly

projecting tongues severally occupying planes oblique to the longitudinal axis of the 40 holder.

7. A horse-tail-holder having inwardly projecting tongues, certain of which are inclined in one direction, and certain others in the opposite direction.

45. 8. A horse-tail-holder having an apertured metal body, and inwardly projecting tongues formed by introverted portions of said metal body, adjacent to the respective apertures severally occupying planes oblique to the 50 longitudinal axis of the holder.

9. A horse-tail-holder having a metal body provided with a longitudinal row of apertures, certain of the walls of which are obliquely inclined, and having obliquely inclined inwardly projecting tongues formed by introverted portions of said metal body bent inwardly along certain of the obliquely inclined walls of said apertures.

10. A horse-tail-holder having a metal 60 body provided with a longitudinal row of apertures, certain of the walls of which are inclined in one direction, and certain of the walls of others of which are inclined in the opposite direction, and having inwardly projecting tongues formed by introverted portions of said metal body bent inwardly along the respective oppositely inclined walls of 65 said apertures.

In testimony whereof, I have hereunto set 70 my hand this 5th day of September, 1907.

ORRIN B. READ.
